DESIGN FOR A CHUCK OR SIMILAR ARTICLE

Frank C. Perry, Detroit, Mich., assignor to Monarch Governor Company, Detroit, Mich., a corporation of Michigan

Application January 17, 1945, Serial No. 117,472

Term of patent 14 years

(Cl. D54—14)

To all whom it may concern:

Be it known that I, Frank C. Perry, a citizen of the United States, residing at Detroit, county of Wayne, State of Michigan, have invented a new, original, and ornamental Design for a Chuck or Similar Article, of which the following is a specification, reference being had therein to the accompanying drawing, forming a part thereof,
in which

Fig. 1 is a perspective view of a chuck or similar article embodying a design in accordance with the present invention.

Fig. 2 is a side elevation thereof.

Fig. 3 is a plan view.

I claim:

The ornamental design for a chuck or similar article, substantially as shown.

FRANK C. PERRY.
